UNITED STATES PATENT OFFICE.

JOSEPH H. HURLBUT, OF SAN FRANCISCO, CALIFORNIA, ASSIGNOR TO THE
PACIFIC INDICATOR COMPANY, OF SAME PLACE.

AUTOMATIC STATION-INDICATOR FOR RAILWAY-CARS.

SPECIFICATION forming part of Letters Patent No. 372,373, dated November 1, 1887.

Application filed May 28, 1887. Serial No. 239,716. (No model.)

To all whom it may concern:

Be it known that I, JOSEPH H. HURLBUT, a subject of the Queen of Great Britain, residing in the city and county of San Francisco and 5 State of California, have invented certain new and useful Improvements in Automatic Station-Indicators for Railway-Cars.

My invention relates to improvements in operating street or station indicators in railway-cars; and it consists in certain novel construction and combination of parts, as hereinafter fully described, for moving a web or apron having the names of streets or stations on it and for operating it in an automatic manner 15 under all conditions of travel of the car along the line of the road. The mechanism is constructed and adapted to reverse the movement of the apron as often as the car changes its direction of travel without calling for adjustment or any attention at such times. It is capable of being applied to work on cars that are turned end for end at the terminus of the road by a turn-table, or otherwise, to present the same end of the car in the direction of 20 travel, as well as of being used on cars that are reversed at the terminus of the road.

The object of my invention is to produce a simple and reliable indicating apparatus or mechanism for railway-cars having these features of adaptation, and requiring also no adjustment or attention when a car is changed from one track to the other, or its direction of travel is reversed.

The following description explains the nature of my said improvements and the manner in which I proceed to construct, apply, and carry out the same, the accompanying drawings being referred to by figures and letters.

Figure 1 is a front view of the indicator with 40 the front of the case taken off and the apron and its guide-rollers omitted. Fig. 2 is a vertical section taken at about the line $x x$, Fig. 1. Fig. 3 is a side elevation of the actuating mechanism that is fixed to the running-gear of 45 the car in close relation to projections fixed on the roadway. Fig. 4 is a top view of the mechanism in Fig. 3. Figs. 5 and 6 show parts in detail. Figs. 7 and 8 show a modification of this actuating mechanism, in which gears are 50 substituted for the belt or chain to operate the indicator in the reverse direction. Figs. 9, 10,

11, and 12 are details of actuating mechanism, in which the levers that make contact with the fixed stops have simple oscillating movement upon a pivot instead of turning around it. Fig. 13 is a view from the right-hand side of Fig. 9. Fig. 14 is a plan of Fig. 13. Fig. 15 shows parts of the mechanism in perspective.

The apron-moving parts of the apparatus 60 are arranged in the car as follows: 2 and 3 are two rollers set in bearings at $a a$ in the inclosing-case 1, above and below the sight-openings. 4 5 6 7, &c., are smaller guide rollers turning loosely in bearings $b b$, and arranged 65 in two sets, of which the set at the back of the case is composed of four rollers, and the other set, having two additional rollers, is arranged just behind the front plate.

The apron C has upon its face the names 70 or matter to be displayed. It is attached by one end to the upper winding-roller, 2, and is carried from beneath it to the front and around the roller 4, that sets just below the line of the opening A^3 , and thence it is carried upward 75 and over the roller 5, above the top of the opening. From this roller the apron is carried above the winding-roller back to the topmost roller, 6, of the rear set, then down to and under the next roller, 7, by which 80 it is turned to the front again. From this roller 7 the apron is brought to the front and over the roller 8 and down to and under the next roller, 9. These rollers 8 and 9 bring the face of the apron in line with the sight-opening A^2 . From the last-mentioned roller the 85 apron is turned back to and over the roller 10, and thence down to and under the bottom roller, 11, which brings it to the front again, where it passes underneath the lowermost 90 roller, 12, and around it to the roller 13, where it is turned backward to the winding-roller 3. By this arrangement of winding-rollers and 95 guide-rollers the apron is brought in line with the three sight-openings A^2 and A^3 and will run smoothly, without excessive friction. The matter on one face of the apron is displayed at the opening A^2 , and that on the reverse side at the openings A^3 . The rollers 7 and 10 are adjustable, for which purpose they 100 are set in slotted hangers 17, held by screws 23, taking through the slots and into the sides

of the case. Different thicknesses of material used for the apron will be found to require adjustment of some of the guide-rollers in order to make the apron wind smoothly and evenly as the layers accumulate on one or the other of the winding-rollers, and by making these rollers movable up or down the desired object will be obtained. The top winding-roller is the driving-roller, and the bottom roller receives movement from it through sprocket-wheels 14, 15 and a drive-chain, 16. One wheel is fixed to its roller; but the other wheel, 15, is fixed on a spindle, 20, that carries the other roller, but to which it is not directly fixed. The spindle passes through the heads of the roller and is attached to one head by the coil-spring 21, which is fastened at one end to the head and at the other end to the spindle.

As the drive-chain 16 connects the two rollers in a positive manner, it is necessary to have one roller yield or turn on its spindle to compensate for the variation in the movements of one roller over the other that takes place at the circumference as the apron runs from one roller and is taken up by the outer roller, and for this purpose the lower roller has a limited yielding movement upon its spindle, but also turns with the spindle by means of its connection through the coil-spring.

For the winding-rollers I use wooden cylinders with metal heads, as shown in Fig. 1.

The apron-carrying mechanism is actuated from the shaft B under the car-floor through the medium of a drive-chain, D, and sprocket-wheels C², 18, of which one is fixed on the lower roller and the other, C², is fixed on the shaft. The drive-chain D passes from the indicator-box through an aperture cut in the casing behind the box and is carried between the inner and outer casing of the car, down to and under the seat, to the shaft B, suitable guide-sheaves, d^x, being set in position to turn and guide the chain. These parts, being covered by the wood-work of the car, are concealed from view and cannot be broken or thrown out of gear by mischievous persons. The shaft B is set in boxes B², under the car and close against the bottom, the chain being carried to the sprocket-wheel C² through openings cut in the car-bottom.

On the shaft B there is secured a wheel with teeth or alternate elevations and depressions, which I shall here describe and refer to as a "star-wheel," the elevations being rounded projections parallel with the axle of the wheel and separated by depressed portions. This star-wheel S (seen at Figs. 9, 10, and 12 in side view and at Fig. 11 in plan) may have friction-rollers m set into the projections. It is fixed on the shaft directly under a stiff plate-spring, M, to set in contact with and receive pressure of the free end of the spring, that is fastened at the other end, V, to some fixed point.

At the free end a sharp bend is formed in the lower face of the spring to present an

acute-pointed tooth or edge, m², parallel with the general axis of the ribs or elevations. As these projections press against the spring 70 in the rotation of the shaft, the acute edge m² will ride upon a projection, and then, after passing over the center, the downward pressure of the spring will throw over the wheel and complete the movement required of the shaft. 75 Only such portion of the whole movement as is sufficient to bring the center or highest part of the projection under the edge m² of the spring is required to be given to the star-wheel, for the spring then produces the remainder of the movement. As often as the star-wheel is thus set in motion the shaft B turns, and the length of this movement is calculated to turn the winding roller 2 a sufficient amount to change the apron. When the 85 elevated point of a star-wheel passes the tooth of the spring, this projecting part slips into a space or depression and locks the wheel until another movement of the shaft takes place. It should be mentioned that this star-wheel and spring may be dispensed with where the construction of the cars and the roadway is favorable to a perfect and reliable coaction of the actuating-levers and the fixed stops. A smooth and solid track and roadway and well-constructed cars may not require this attachment to insure the proper amount of rotation in the shaft B. The mechanism actuating this shaft is fixed on the truck or upon some portion of the running gear not affected by the rise and fall or oscillations of the car-body on its springs. It is set to engage with stops or projections P fixed along the roadway and sufficiently raised above the surface between the tracks. In its simplest form it consists of several bent arms 90 95 or levers rigidly fixed on a shaft in a radial manner to present their ends in close relation to the projection P.

The bent end of the lever extending forward of the pivot is carried along in close relation to the surface and in the line of the projections P by the movement of the car along the track. The shaft H² has bearings in the plates II, that are fixed to some part of the truck not affected by the motions of the car body, and the driving belt or chain g is carried from a pulley or sprocket wheel, c³, on the shaft H² up to and around a similar wheel on the shaft B above. As the bearings of this shaft B are fixed on the car-body, it is subject to more or less vertical movement, and its position with reference to the shaft below changes under the motion of the car-body. To compensate for this, I place floating pulleys E² between the two sprocket-wheels and carry the drive-chain g over them. The shaft B² of these guide-pulleys is carried by links m^x m^{xx}, one set of which, extending from the lower shaft, meets the other set, m^x, from the principal shaft, as shown in Figs. 3 and 4. A sufficient number 125 130 of lever-arms H³ is employed to make one arm, when it is turned by one projection P, bring and leave another arm in position to meet the next projection. In the construction here

given four arms are fixed on the shaft H^2 , and the length of movement produced at the shaft B is calculated to move the indicator-apron the required distance at each time.

5 It will be seen that by providing each arm with two projecting ends facing in opposite directions, as shown in Fig. 6, the mechanism will operate whether the car is traveling forward or backward. This construction is applicable to cars that are shifted from one track to another, by a turn-table or otherwise, to present the same end in the direction of travel, and also to cars that are turned end for end, by substituting the form of levers in Fig. 6 for the one shown in Figs. 3 and 5.

Instead of employing the cross-chain and guide pulleys to produce the reverse or contrary movement, however, the arrangement of gearing and chains shown in Figs. 7 and 8 can be used to advantage. In such case the intermediate shaft, B^5 , is geared into the shaft above by spur-gears $G^1 G^2$, and one set of lever-arms, H^3 , that comes in action to produce the contrary movement of the shaft B where the car is switched or shifted to the other track, is connected with the shaft B^3 by sprocket-wheels E^6 and chain g^3 . The other set of lever-arms, H^4 , on the other side of the center line of the track, is connected directly to the shaft B by sprocket-wheels and chains C^3 , E^7 , E^8 , and $g^4 g^5$. In its operation, therefore, this arrangement of the mechanism turns the shaft B in one direction or the other, according as one set or the other of the lever-arms is in action. When one set is engaging with the line of fixed stops in the track, the other set of arms, being out of line, does not work, and vice versa. The two sets of arms H^3 and H^4 therefore turn independently of each other on the center H^2 , which in this case is a fixed shaft. In this construction a star-wheel, S , is fixed on the center of each of the lever-arms $H^3 H^4$ instead of the shaft B . The levers $R R^x$, Figs. 9, 10, 11, 12, have oscillating movement instead of rotation upon the center H^2 , and this movement, being produced by contact of the roller on the projecting end with the fixed stops P , is caused to turn the shaft B a given portion of a revolution through the me-

50 dium of a pawl-and-ratchet-wheel connection between the upper end of the lever and the shaft. Two of these levers are placed side by side on opposite sides of the center line of the track, and the stops P in each track are set on the same side, so that one lever is in action while the car is on one track and the other lever when the car is returning on the other track. The horizontal member R^2 of the lever is furnished with a traction-wheel, K , and the end of the upright part is connected by a rod, G^4 , to an oscillating lever, F^2 , that is attached at f to the car-body. To this lever is attached, by a pivot-joint, the ends of the rods $F F^x$, furnished with hooks $F^3 F^3$ on the opposite ends. One hook F^3 is set under and the other hook above the ratchet-wheel to work in contrary directions, and

when one is in action the other takes such position that the projections of the wheel readily pass over the hook without catching, 70 while the other hook acts to turn the wheel. The two levers are pivoted at H^2 in the box I^x , that is suspended from the axle-boxes by braces $W W$, in close relation to the surface of the roadway, to bring the wheels $K K^x$ in position to stand in the path of the projections P . As thus placed and connected, one lever, R , of the set engages with the stops P , that are fixed in line on one track to move this lever, but to clear the roller K^x of the other lever, while 80 the transfer of the car at the end of the route to the other track brings the other lever, R^x , into line with the stops on that track, and the operation of the mechanism is reversed.

Having thus fully described my invention, 85 what I claim, and desire to secure by Letters Patent, is—

1. The combination, with the drums or rollers connected together to be driven positively one by the other and adapted to move a web 90 or apron carrying names or matter to be displayed, as described, of the shaft B , sprocket-wheels $C^2 18$, floating pulley F^4 between them, and drive-chain D , the levers pivoted and movable in bearings on the truck-frame or running-gear of the car, having ends projecting on the path of fixed stops, as P , in the track to engage with and be moved by said stops in passing over them, and mechanism, substantially as herein described, connecting said levers and said shaft B positively together for producing intermittent and partial rotation of the shaft at each time of contact with said stops, as herein set forth. 95

2. In a station-indicator apparatus for railway-cars, the combination of the intermittently-rotating shaft B , adapted, by its connection with the indicator-box above, to move the web or apron mechanism thereof, the star-wheel S , and spring M , mounted over and bearing upon 100 the star-wheel, and mechanism, substantially as herein described, fixed on the truck or running-gear of the car in relation to stops or projections on the roadway to be actuated by contact therewith, and by such contact to turn the 105 said shaft B , as herein described.

3. In a station-indicator apparatus for railway-cars, the combination, with the principal actuating shaft B , of the intermediate shaft, $B^3 B^5$, geared together as described, revolving 110 lever-arms $H^3 H^4$, mounted below the intermediate shafts, sprocket-wheels $C^x C^3$ and $E^6 E^7 E^8$, drive-chains $g^3 g^2 g^3 g^4$, and gears G^1 and G^2 , connecting the parts $H^3 H^4$ to the main shaft, all constructed and applied to operate 115 substantially as hereinbefore described.

4. The combination, with the shaft B , adapted to operate the indicator in the car, of the star-wheel S , shaft H^2 , with radial arms or levers presenting bent ends in the path of projections on the roadway, links $m^x m^x$ and m^{xx} m^{xx} , connecting shafts B and H^2 , and pulleys mounted in said links and drive chains therefor, as set forth. 130

5. The combination, in a suitable case, of the web or apron having matter for display arranged on both sides, the winding-rollers 2 3, the series of rollers 4 5 8 9 12 13 at the 5 front, and the rollers 6 7 10 11 at the back, set with relation to the said openings as described, the actuating-shaft B, and connecting drive-chain and sprocket-wheels, and mechanism, substantially as described, actuated by 10 stops or projections in the roadway, whereby rotation of said shaft B at intervals is automatically produced through the movement of the car on its track.

6. The combination of the indicator-case 15 having sight-openings A² A³ A³, and the guide-rollers arranged at the front and back with respect to said openings, so as to present one side of the apron to the center opening and the other side to the other openings, as described, the winding-rollers 2 3, connected by 20 chain and sprocket-wheel, the spindle 20, extending through roller 3, and spring 21, secured at one end to spindle 20 and at the other to the head of the roller, all constructed and 25 applied for operation as set forth.

7. The combination, in a suitable case having sight-openings A² A³ at one side or front,

of the apron-winding rollers 2 3, guide-rollers 4 5 6 8 9 11 12 13, adjustable rollers 7 and 10, spindle 20, spring 21, connecting the roller to 30 its spindle, the drive-chain 16, sprocket-wheels 14 and 15, and mechanism connected with one of said rollers to rotate the same in either direction.

8. In a station-indicator apparatus for rail-way-cars, arms or levers on the truck or running gear of the car or formed to present substantially horizontal ends or members in the path of projections P, fixed in the roadway and to be moved by contact thereof, the 40 sprocket-wheels C² 18, and drive-chain D, connecting the indicator-actuating mechanism above with the shaft B, and connecting pulleys and chains or equivalent gearing connecting said levers with the said shaft B for producing movement of the indicator web or apron in one or the other direction, as set forth.

In testimony that I claim the foregoing I have hereunto set my hand and seal.
